UNITED STATES PATENT OFFICE.

RICHARD F. KENEHAN, OF NEW YORK, N. Y., ASSIGNOR OF ONE-HALF TO
JOSEPH P. DOWDALL, OF NEW YORK, N. Y.

AUTOMATIC CUT-OFF FOR GAS-PIPES.

SPECIFICATION forming part of Letters Patent No. 737,113, dated August 25, 1903.

Application filed January 17, 1903. Serial No. 139,461. (No model.)

To all whom it may concern:

Be it known that I, RICHARD F. KENEHAN, of the borough of Manhattan, in the city, county, and State of New York, have invented certain new and useful Improvements 5 in Automatic Cut-Offs for Gas-Pipes, of which the following is a specification.

My improvement relates to mechanism for automatically shutting off the supply of gas 10 in case of fire and before the gas enters the easily-fusible lead pipes ordinarily used about the connections with the meter.

In case of fires in buildings, and especially 15 in the lower part and basement of buildings, where the gas-meters are usually placed, very frequently the heat is sufficient to melt the lead pipes about the meter and to allow a full force of gas from the supply-pipe to escape, filling the lower parts of the building with 20 gas, aggravating the fire, and seriously endangering the lives of the firemen or other persons who may be obliged to enter the building. It is usual to use an iron pipe for the supply-pipe, leading to the gas-main, and 25 this supply-pipe is connected by a lead connection with the gas-meter. This iron pipe will withstand very intense heat before melting so as to allow the escape of the gas, and I place the automatic cut-off in the iron pipe 30 or directly connected therewith and construct it of metal which will withstand very intense heat, so that if the lead pipes are melted the cut-off will come into operation and stop the gas with its injurious effects.

35 In Figure I of the drawings I have shown an elevation of a gas-meter provided with my automatic cut-off, the cock of which is shown partially in section in order to make the construction clear. Fig. II is a side view, 40 and Fig. III an edge view, of metal disks which may be joined by a soft solder to connect the sections of the wire.

A is a gas-meter.

B is the feed-pipe connecting with the distributing-pipes of the building.

C is an iron supply-pipe connecting with the street-main.

D is a lead connecting-pipe through which the gas-supply reaches the meter.

50 E is a cut-off cock, made of iron or other metal which will withstand intense heat. It

is provided with a weighted lever-arm F, which is adapted to close the cock when the arm is depressed and open the cock when the arm is raised.

55 G G represent the sustaining-wire, formed of sections connected by one or more readily-fusible joints, as g g. This wire is attached at one end to any suitable fastening H and at the other end is connected with the lever F, as at i. I prefer to use for the fusible joints in this wire a composition which will melt at a low temperature, even below 200° Fahrenheit, and considerably below the melting-point of lead, so that in case of fire about 60 the meter before the heat becomes sufficiently intense to melt the lead connections and allow the gas to escape the fusible joint of the sustaining-wire will be melted, freeing 65 the wire and lever-arm F, which, dropping, 70 will effectually close the cock E. m and n are hard metal disks, each attached to a section of the wire G and united by soft solder, the broad surfaces of the disks so dividing 75 the strain that the joint will sustain considerable weight. I prefer to place the fusible jointed wire in quite close proximity to the lead pipes, so that any heat which might seriously affect the pipes will operate also on the 80 fusible joints, and it will be readily understood that the wire can be so arranged with a number of joints in it that some of the joints can be carried near the inlet-pipe and other joints carried near the outlet-pipe, so 85 that heat at either point will release the weight and cut off the gas.

Another advantage of my construction is that in case of the breaking or crushing down of the building the debris striking the lever-arm F will readily break the sustaining-wire 90 G G and allow the lever to cut off the gas. The exact position and adjustment of the cut-off cock must be, of course, modified to suit the various positions of the supply-pipe with the meter; but this will be understood 95 by any gas-fitter or plumber.

It will be readily understood that my improvement is not limited in its application to pipes which convey gas only, but is also applicable to pipes which are used to convey 100 other inflammable fluids, such as petroleum and the like, and in which it is desirable to

shut off the flow of the fluid when a dangerous degree of heat may be reached accidentally or otherwise.

Having thus described my invention, what 5 I claim, and desire to secure by Letters Patent of the United States, is—

1. The combination, with a pipe conveying an inflammable fluid, of a cut-off valve, valve-governing mechanism embodying metallic 10 sections provided with corresponding expanded faces joined by a soft solder fusible at a lower degree of heat than the other attachments, and mechanism for automatically operating said cut-off valve upon the fusing 15 of the joints of any of said metallic sections, substantially as described.

2. The combination, with a pipe conveying an inflammable fluid, of a cut-off valve held normally open by a valve-governing mechanism 20 embodying sections of wire provided at their ends with metallic disks, said disks being united in pairs by a soft solder fusible

at a lower degree of heat than the other portions of said attachments, and mechanism for closing said valve automatically when released by the fusing of any of the soldered joints, substantially as described. 25

3. The combination, with a pipe conveying an inflammable fluid, of a cut-off valve held normally open by a valve-governing mechanism 30 embodying sections of wire provided at their ends with metallic disks, said disks being united in pairs by a soft solder fusible at a lower degree of heat than the other portions of said valve-governing mechanism, and 35 mechanism, consisting of a gravity-lever, for closing said valve automatically when released by the fusing of any of the soldered joints, substantially as described.

RICHARD F. KENEHAN.
